(57) **CLAIM**

We claim the ornamental design for an interactive toy, as shown and described.

DESCRIPTION

FIG. 1 is a left front perspective view of an interactive toy showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof; and,

FIG. 7 is a bottom plan view thereof.

The broken lines shown in FIG. 7 are included for the purpose of illustrating a portion of the interactive toy that forms no part of the claimed design.
